UNITED STATES PATENT OFFICE.

JOSEPH E. THAYER, OF EAST BRIDGEWATER, MASSACHUSETTS, ASSIGNOR TO UNITED SHOE MACHINERY COMPANY, OF PATERSON, NEW JERSEY, A CORPORATION OF NEW JERSEY.

BOBBIN-HOLDING DEVICE FOR LOCK-STITCH SEWING-MACHINES.

1,024,708.

Specification of Letters Patent.

Patented Apr. 30, 1912.

Application filed February 15, 1905. Serial No. 245,697.

To all whom it may concern:

Be it known that I, JOSEPH E. THAYER, a citizen of the United States, residing at East Bridgewater, in the county of Plymouth and State of Massachusetts, have invented certain new and useful Improvements in Bobbin-Holding Devices for Lock-Stitch Sewing-Machines; and I do hereby declare the following to be a full, clear, and 10 exact description of the invention, such as will enable others skilled in the art to which it appertains to make and use the same.

The present invention relates to an improvement in bobbin holders for lock stitch 15 sewing machines.

In the Goodyear "Rapid" stitcher, which is illustrated with substantial accuracy in the patent to French and Meyer, No. 473,870, the bobbin case, or bobbin, as the bobbin 20 and bobbin case are generally referred to, is placed loosely in the oscillating shuttle and held there during the operation of the machine by a bobbin holding arm which engages the face of the bobbin and prevents its displacement. For convenience in removing 25 and replacing the bobbin the bobbin holding arm is pivoted to a bolt supported in a bracket projected from the side of the shuttle race. By tightening the nut on the 30 bolt the bobbin holding arm is frictionally held in place. A leather washer under the nut is relied upon to create the necessary friction to hold the bobbin arm from displacement in the operation of the machine.

35 See patent to French and Meyer, No. 424,966. In this construction the bobbin holding arm is held in place solely by frictional means, and those means have been found ineffective owing to the fact that in the operation of 40 the machine the jar of the parts, and particularly the jar of the bobbin against the bobbin holder, tends to loosen the nut which holds the bobbin holding arm in place. It has also been proposed in a lock 45 stitch sewing machine to hold the bobbin holding arm in place by a T-headed bolt which passed through a slot in the bobbin holding arm and was then turned to engage and hold the bobbin holding arm in place.

50 In this construction, however, this bolt was still more liable to be turned in the operation of the machine into the position to release the bobbin holding arm.

The object of the present invention is to produce an improved construction of bobbin holding means in which the bobbin arm is positively held in place, that is, held in place so that it cannot become loosened or displaced by the jars incident to the operation of the machine. 55

To the above ends the present invention consists in the devices and combinations of devices hereinafter described and particularly defined in the claims. 60

In the accompanying drawings illustrating the preferred form of the invention Figure 1 is a front elevation of the shuttle race and bobbin holding means, and Fig. 2 is a plan of the same, the parts being shown as adapted to be incorporated in the 70 machine of the said French and Meyer Patent No. 473,870, to which for a description of the parts not hereinafter mentioned reference may be had. 65

The shuttle race 1, adapted to receive the 75 shuttle and the bobbin therein, is substantially the same as in said patented machine. The bobbin holding arm 2 is pivoted upon the bolt 3 which is carried by a bracket 4 secured to the head of the machine. The 80 axis of movement of the bobbin holding arm is vertical so that the bobbin holding arm moves toward and from the bobbin. A stop screw 5 having a lock nut thereon passes through a threaded aperture in the 85 arm 2 and engages the periphery of the shuttle race 1. This affords means for limiting the movement of the bobbin arm toward the bobbin. A latch 6 is provided to hold the shuttle arm in operative position, which 90 latch is pivoted upon the cap bolt 7 which screws into the bracket 4. The axis of the bolt 7 is arranged at right angles to the axis of movement of the bobbin arm and parallel to the axis of the shuttle movement. When the latch 6 occupies the position illustrated by full lines in Fig. 1 it positively holds the shuttle arm from swinging upon its support away from the bobbin by the engagement of an adjusting screw 100 8, located in the end of the latch with the bobbin arm. The screw 8 is provided with a set nut by means of which the screw is locked in place against accidental displacement by the jar of the machine. When the 105 bobbin holding arm is adjusted by means of

the screw 5, to swing farther in the adjusting screw 8 must be correspondingly adjusted and vice versa.

The latch 6 is normally held in its locking position by means of a spring-pressed pin 9 which is supported in a hole in the bracket 4 and adapted to slide back and forth therein to engage a recess 10 in the face of the latch 6. When the latch occupies the position shown by the full lines in Fig. 1, the spring-pressed pin 9 is in engagement with the recess 10 and yieldingly holds the latch 6 from being moved from such position. A screw 11 is provided for limiting the movement of the spring-pressed pin 9. By turning the latch 6 to the position illustrated in dotted lines in said figure the latch is disengaged from the bobbin holding arm 2 and the arm may be swung outwardly to permit removal and replacement of the bobbin in the shuttle. This construction affords efficient means for positively holding the bobbin holding arm in operative position without liability of accidental displacement, the latch 6 affording a positive support for holding the bobbin holding arm from displacement.

The invention is applicable to different forms of lock stitch sewing machines, and may be embodied in other forms than that illustrated in the drawing and described herein without departure from the following claims.

Having now described the invention what is claimed is:

1. A lock-stitch sewing machine, having, in combination, a bobbin, a bobbin holding arm pivotally mounted to swing toward and from the bobbin, and a latch constructed to engage and positively hold the bobbin holding arm in operative position, said latch being provided with an adjusting screw by means of which the position of the surface of engagement with the bobbin holding arm may be determined, substantially as described.

2. A lock-stitch sewing machine, having, in combination, a bobbin, a bobbin holding arm pivotally mounted to swing toward and

from the bobbin, an adjustable stop to determine the operative position of said arm and a latch constructed to engage and positively hold the bobbin holding arm in operative position, said latch being provided with an adjustable screw by means of which the position of the surface of engagement with the bobbin holding arm may be determined, substantially as described.

3. A lock stitch sewing machine, having, in combination, a bobbin, a bobbin holding arm pivotally mounted to swing toward and from the bobbin, a latch constructed to engage and positively hold the bobbin holding arm in operative position and a spring pressed locking device movable into and out of locking position to hold the latch in engagement with the bobbin holding arm, substantially as described.

4. A lock stitch sewing machine, having, in combination, a bobbin, a bobbin holding arm pivotally mounted at one side of the bobbin to swing toward and from the bobbin, and a latch constructed to engage the bobbin holding arm on the same side of the pivot as the bobbin and hold the bobbin holding arm in operative position, said latch being pivotally mounted upon a pivot having its axis at right angles to the axis of the bobbin holding arm and being arranged to engage the surface of the arm away from the bobbin, substantially as described.

5. A lock stitch sewing machine, having, in combination, a bobbin, a bobbin holding arm pivotally mounted to swing toward and from the bobbin, a latch pivotally mounted upon a pivot having its axis at right angles to the axis of the bobbin holding arm, and a spring pressed locking device to engage the latch when the latch is in position to engage and hold the bobbin holding arm in operative position, substantially as described.

In testimony whereof I affix my signature, in presence of two witnesses.

JOSEPH E. THAYER.
